(57) **CLAIM**

The ornamental design for a motorcycle trailer, as shown and described.

DESCRIPTION

FIG. 1 is a perspective view of a trailer of the present invention.

FIG. 2 is a right side elevation view of the trailer of FIG. 1, the left side view being a mirror image thereof.

FIG. 3 is a top plan view of the trailer of FIG. 1.

FIG. 4 is a rear elevation view of the trailer of FIG. 1; and,

FIG. 5 is a front elevation view of the trailer of FIG. 1.

The broken lines of FIGS. 1-5 are for environmental purposes only and form no part of the claimed design.

1 Claim, 2 Drawing Sheets Fig. 1

Fig. 2

Fig. 3

Fig. 4

Fig. 5
